A handwritten signature in cursive script, appearing to read "Wm. J. Muller" or a similar name.

ATTORNEYS

UNITED STATES PATENT OFFICE.

GEORGE A. C. GOETTING, OF NEW YORK, N. Y.

DESIGN FOR WRAPPING-PAPER.

SPECIFICATION forming part of Design No. 33,667, dated December 4, 1900.

Application filed November 8, 1900. Serial No. 35,870. Term of patent 14 years.

To all whom it may concern:

Be it known that I, GEORGE A. C. GOETTING, a citizen of the United States, and a resident of the city of New York, borough of Manhattan, in the county and State of New York, have invented and produced a new and original Design for Wrapping-Paper, of which the following is a specification, reference being had to the accompanying drawing, forming a part thereof, in which is represented a section of wrapping-paper embodying the features of my design.

The leading features of my design consist of a grouping of figures representing skulls and crossed bones, the skulls being arranged in a circle, with their crown toward the center of such circle. The crossed bones are also cir-

cularly arranged, a pair of crossed bones being adjacent to the jaw of each skull.

A minor feature of the design consists in an outer circle composed of smaller-sized skulls and crossed bones, within which outer circle the larger figures are contained.

Having thus described my invention, I claim as new and desire to secure by Letters Patent—

The design for wrapping-paper as herein shown and described.

In testimony whereof I have signed my name to this specification in the presence of two subscribing witnesses.

GEORGE A. C. GOETTING.
